CLAIM

The ornamental design for a basket, as shown and described.

DESCRIPTION

FIG. 1 is a front, left and upper perspective view of a basket showing my new design.

FIG. 2 is a front view thereof;

FIG. 3 is a rear view thereof;

FIG. 4 is a right side view thereof;

FIG. 5 is a top plan view thereof; and,

FIG. 6 is a bottom plan view thereof.

The broken lines illustrate portions of the basket that form no part of the claimed design.

1 Claim, 6 Drawing Sheets
